(57) **CLAIM**

We claim the ornamental design for a bag, as shown and described.

DESCRIPTION

FIG. 1 is a perspective view of the bag of the claimed design; FIG. 2 is a front view of the bag; FIG. 3 is a rear view of the bag; FIG. 4 is a top view of the bag; FIG. 5 is a bottom view of the bag; FIG. 6 is a left side view of the bag; and, FIG. 7 is a right side view of the bag.

The ornamental design which is claimed is shown in solid lines in the drawings. The broken lines shown in FIGS. 1, 2, 4, 6 and 7 illustrate portions of the bag that form no part of the claimed design.

1 Claim, 7 Drawing Sheets
